CATHODE RAY TUBE

Lewis Barnard Headrick, Short Hills, N. J., assignor to Radio Corporation of America, a corporation of Delaware

Application August 20, 1937, Serial No. 160,009

4 Claims. (Cl. 250—163)

This invention relates to cathode ray tubes and more particularly to means for concentrating and focusing the electron ray as produced by the tube.

5 In many of the systems in which cathode ray tubes at present are used, it is desirable that the ray itself should be of as high a concentration as possible, that is, its cross-sectional area should be as small as possible. These qualifications are 10 particularly desirable when the cathode ray tube is used as an oscilloscope or when used in the transmission or reception of television programs. In the case of the latter, the quality and definition of the picture image as produced by the 15 transmitting tube or "Iconoscope" or as produced by the television receiver is to a certain extent dependent upon how small the cross-sectional area of the beam can be made at the point at which it strikes the photoelectric mosaic or the 20 fluorescent screen.

In condensing the cathode ray into a very small beam, a series of electrostatic and/or electromagnetic lenses are used and in the use of such lenses a certain amount of spherical aberration has heretofore been present. Because of this spherical aberration it has been difficult to 25 reduce the cross-sectional area of the beam to the desired degree and it is therefore one purpose of the present invention to provide a gun structure for producing a cathode ray beam wherein the effect of spherical aberration is substantially or completely overcome.

A further purpose of the present invention is to produce a cathode ray tube in which the 30 beam produced by the tube may be concentrated and focused into a very small spot.

A still further purpose of the invention is to produce a cathode ray tube having the above named advantages, while at the same time the 35 physical construction and mode of fabrication of the tube is not materially changed with the result that the necessary changes in the production thereof are not great.

Other purposes and advantages of the present 40 invention will become apparent to those skilled in the art from a reading of the following specification, wherein like reference numerals indicate like parts, and in which:

Figures 1 and 2 represent examples of the present 45 or known manner of constructing cathode ray tubes, and

Figures 3 and 4 represent the improved method of constructing cathode ray tubes in accordance with the present invention.

50 Referring to the drawing, the envelope for con-

taining the cathode ray gun structure is indicated generally at 10 in the figures, and may be made of metal, or some vitreous substance such as glass, or in fact any other appropriate material. Contained within the envelope is a filament element 11 which may be heated by any appropriate means and most desirably by electricity for supplying heat to the emitter or cathode element 12. This emitter element is preferably coated with a material which is high in 10 electron emitting quality as is usual in such tubes.

In Figure 1 the control electrode 13 is shown primarily as an apertured disk which is positioned forward with respect to the emitter. This 15 electrode is normally maintained negative with respect to the emitter and, by applying varying potentials to this electrode, the intensity of the cathode ray beam may be controlled. Beyond the control electrode 13 is positioned the first 20 accelerating anode 21, with, in cooperation with the second anode 22, produces a field which causes the cathode ray beam to be focused into a relatively small area. This focusing action is also aided by the differences in potential between the control electrode and the first anode 21 as well as by the current limiting apertures 25 as shown in the first anode. In this figure the control electrode 13 affects the intensity of the cathode ray beam by the action of the field in 30 the aperture of the control electrode.

In Figure 2 the control electrode 4 is modified slightly in that a skirt portion 15 is provided therefor. The presence of this skirt portion produces a varying field intensity because of the 35 difference in potential between the control electrode and the first anode, which, together with the aperture in the control electrode, determines the intensity and, to a certain degree, the focusing of the produced cathode ray beam. In each 40 of these figures it will be seen that the control electrode is positioned forward with respect to the emitter, and, in each of these tubes, a certain amount of spherical aberration is present.

In Figure 3, and in accordance with this invention, it will be seen that the control electrode 16, together with the skirt portion or cylindrical extension 17, is so positioned that the emitter lies in the plane of the control element, with the 45 activated end portion of the emitter lying entirely within the aperture of the control electrode. Because of this construction, the varying potentials applied to the control electrode affect the cathode ray beam only by the presence of 50 55

the cylindrical section or skirt 17 and in no way by the field at the aperture per se.

In Figure 4 is shown another form of the invention in which the control electrode 18 includes a cylindrical extension 19 and a frusto-conical member 20. The emitter element is placed in the plane of the small diameter end of the frusto-conical member as shown in the figure, and the first anode 21 is positioned forward with respect to the large diameter end of the member. By using a frusto-conical control electrode it is possible, by varying the angle of the conical member 20, to change the field shape and accordingly the control action to give a particular desired control and focusing field. Also, the curvature of the field near the cathode or emitter can be made substantially constant over the beam cross-section. The use of the frusto-conical member results in an elimination of all or substantially all of the spherical aberration that is present to a certain degree in tubes of the usual construction as shown in Figures 1 and 2.

It may be seen from the above that the construction and location of the control electrodes 16 in Figure 3 and 18 in Figure 4 differ from that usually employed in cathode ray tubes with the result that the control action of the beam is the result of the presence of the cylindrical section alone as at 17 in Figure 3 or by the frusto-conical member 20 as in Figure 4. By eliminating the spherical aberration, as stated above, it is possible to produce better focusing of the beam with the result that the cross section diameter of the beam at the point of focus, that is, at the point where the beam strikes a photo-sensitive mosaic, a fluorescent screen, or the like, is materially reduced and such reduction in size permits of increased detail in the image being produced by the beam. It is to be understood that the particular control electrode structure as described above in reference to Figures 3 and 4 in accordance with the present invention, may be used with any appropriate anode structure and that the structure of the first and second anodes as shown in the drawing is only by way of example and may be changed without departing from the spirit of the applicant's invention. This is true also with respect to the emitter, since it is only necessary that the emitter, regardless of its type, be placed in the plane of the member which is perpendicular to the axis of the control electrode as shown in Figure 3 or in the plane of the small diameter end of the frusto-conical member as in Figure 4.

It is also to be understood that any specific deflecting means for the cathode ray beam could be used since this forms no part of the applicant's invention, and, as a matter of fact, the deflecting means is not shown. Either electro-static or

electro-magnetic deflection may be used or any combination of these means.

Various modifications and alterations may be made in the present invention without departing from the spirit and scope thereof, and it is desired that any and all such modifications be considered as within the purview of the present invention except as limited by the hereinafter appended claims.

What I claim is:

1. A cathode ray tube, means for producing and focusing or condensing a stream of electrons comprising an electron emitter, at least one accelerating electrode and a control electrode; said control electrode being in the form of a frusto-conical member and means for coaxially positioning the member between the emitter and the accelerating electrode with the emitter in the plane of the smaller end of the member and with the larger end of the member facing the accelerating electrode. 10 15 20

2. A cathode ray tube including a gun structure for producing a stream of electrons, said structure comprising an electron emitter, at least one accelerating electrode and a control electrode, 25 said control electrode comprising a centrally perforated disc so positioned that the emitter lies in the plane of the disc and in the perforation thereof, an annular extension attached to the disc in region of the periphery thereof and extending 30 in the direction of the accelerating electrode and a frusto-conical member positioned between the end of the annular extension and the perforation of the disc member.

3. A cathode ray tube, means for producing a 35 stream of electrons comprising an emitter and at least one accelerating electrode, a control electrode positioned between the emitter and the accelerating electrode, said control electrode being in the form of a frusto-conical member, so positioned that the said emitter lies in the plane 40 of the smaller end of said member, the larger end of said member facing in the direction of said accelerating electrode. 45

4. A cathode ray tube, means for producing 45 and focusing a stream of electrons comprising an electron emitter, at least one accelerating electrode and a control electrode, said control electrode being in the form of a frusto-conical member, and means for positioning said member between the emitter and the accelerating electrode 50 with the emitter in the plane of the smaller end of the member, and with the larger end facing in the direction of said accelerating electrode, whereby changes in the potential of said control electrode will affect only the intensity of the 55 stream of electrons.

LEWIS BARNARD HEADRICK.
